ATTY.

UNITED STATES PATENT OFFICE.

JOHN WESLEY BOOTH, OF TRENTON, ONTARIO, CANADA.

TONE-ARM.

1,385,358.

Specification of Letters Patent. Patented July 26, 1921.

Application filed March 10, 1920. Serial No. 364,707.

To all whom it may concern:

Be it known that I, JOHN W. BOOTH, a citizen of the United States of America, and resident of the town of Trenton, in the 5 county of Hastings, Province of Ontario, Dominion of Canada, have invented certain new and useful Improvements in Tone-Arms, of which the following is a specification.

10 This invention relates to improvements in tone arms for sound reproducing machines, and the objects of the invention are to provide a simple and effective tone arm in which the tone passage will be free from obstruction, and may be freely supported to enable it to perform effectively the functions required of it, and move over the record.

More specific objects are to provide an 20 improved form of spring support for the tone arm and an improved joint between the tone arm and base, which will avoid any interference with sound rays passing through the tone arm.

25 Still further objects are to obtain mellowness of tone, freedom from unnecessary vibration and smoothness of action on the record.

The invention consists essentially of the 30 improved construction, hereinafter described in detail in the accompanying specification and drawings;

In the drawings;

Figure 1 is a sectional elevation showing 35 an embodiment of my invention.

Fig. 2 is an end elevation.

Fig. 3 is a sectional plan taken on the line 40 $x-x$ of Fig. 1.

Fig. 4 is a detail sleeve containing a supporting spring.

In the drawings, like characters of reference indicate corresponding parts in all the figures.

Referring to the drawings, A indicates 45 the motor board, and B the tone arm, which is pivotally mounted with freedom to turn about a vertical axis, and a supporting sleeve C, the end of the tone arm being formed with a ball 10, which fits the socket 50 11 in the sleeve, and a pivotal pin 12 connecting the tone arm and socket.

The sleeve C is formed with a projecting annular flange 14 extending over the inside of the bearing member D, and constitutes 55 the tone passage 13.

To prevent escaping of tone between the

members D and C I preferably provide a felt lining or packing 15, between the two members. The return movement between the two members D and C is limited by 60 means of a spring plunger 16 mounted in a recess 17 in the member C and engaging arcuate slots 18 in the member D.

Spring support is given to the tone arm by means of a spiral compression spring 18 65 contained within a sleeve 19 supported from a bracket 20 connected to the member C.

The spring 18 presses at opposite ends against plungers 21 and 22 which fit the sleeve, movement of the plungers being limited by pins 23 and 24 thereon, which operate in slots 25 and 26. The slot 25 is formed with one lateral slot or step 27, while the slot 26 is formed with three lateral slots or steps 28 and 29 and 30. 75

It will be seen that by adjusting the plungers 21 and 22 by engaging the pin 24 with either one of the slots or steps 28, 29 or 30. The tension of the spring 18 may be adjusted the same way at the upper end. The 80 tension on the tone arm might be released by moving the plunger downwardly and engaging the pin 23 with the slot or step 27.

The plunger 21 is conveniently formed with a round end, and will engage a bearing 85 plate 31 on the tone arm.

It is seen that the foregoing provides simple and effective means of adjusting the spring supporting pressure on the tone arm. This is accomplished without any interference with the tone passage, which is quite 90 free from obstruction. This taken with the tight joint produced by the felt packing 15, and the general construction of the member C enables the remarkable mellowness of tone 95 to be produced, together with freedom from unnecessary vibration and smoothness in action on the record.

The tone arm may be formed of wood or metal or other convenient material, such as 100 rubber composition or the like.

As many changes could be made in the above construction, and many apparently widely different embodiments of my invention, within the scope of the claims, constructed without departing from the spirit or scope thereof, it is intended that all matter contained in the accompanying specification and drawings shall be interpreted as 105 illustrative, and not in a limiting sense. 110

What I claim as my invention is:—
1. A resilient support for pivotally

- mounted tone arms, comprising a cylinder, a plunger slidably mounted in one end of said cylinder to project therefrom, a plug closing the opposite end of said cylinder 5 and slidably mounted therein, a plunger projecting spring confined between said plunger and plug, said plug being slidable in the cylinder relative to the plunger to vary the tension of the intervening spring, 10 and coöperating means carried by said plug and cylinder for supporting the plug in the cylinder and locking it in adjusted position therein.
2. In a device of the character described, 15 a tone arm having a downwardly turned inner end, a sleeve pivotally connected to the tone arm, a bracket connected to the outer side of the sleeve and extending outwardly therefrom, a vertically extending sleeve car-

ried by the bracket, a spring therein, and a plunger carried by the spring adapted to engage the tone arm at a distance outwardly from its pivotal point.

3. A resilient support for a pivotally mounted tone arm comprising a cylinder, a plunger slidably mounted in one end of said cylinder to project therefrom, a spring contained within the cylinder and normally tending to force the plunger upwardly, and means for limiting the outward movement 30 of said plunger, and locking the plunger in retracted position.

In witness whereof I have hereunto set my hand in the presence of two witnesses.

JOHN WESLEY BOOTH.

Witnesses:

JOHN LAINARD,
THOMAS ALFRED O'ROURKE.
